ANTISLIPPING DEVICE

George A. Moriarty, San Diego, Calif.

Application October 8, 1937, Serial No. 167,928

12 Claims. (Cl. 36—7.7)

This invention relates to antislipping devices adapted to be associated with the soles of shoes and the like for the purpose of giving the wearer a more secure footing on a walking surface.

Such devices find wide application in many fields where it is necessary or desirable that slipping between the sole of the shoe and the walking surface be avoided. Hill climbing, lumbering, walking on ice and various sports, as golf and baseball, are examples of some of the fields in which the present invention has application.

It is an object of the invention to provide an antislipping device which is simple in construction and economical to produce.

It is another object of the invention to provide an antislipping device which is readily adjustable to fit shoes of various sizes.

Another object of the invention is to provide an antislipping device which is not only easily applied to a shoe but which when applied to the shoe will automatically move into secure operative relation therewith.

A feature of the invention, therefore, resides in providing an antislipping device which is maintained in operative relation with the shoe by means of a resilient connection between the device and a means engaging the shank portion of the shoe sole.

Another feature of the invention resides in providing a pair of pivotally connected and crossed members adapted to be positioned beneath a shoe sole and having projecting means thereon for engaging a walking surface; and in providing a resilient connection between the respective crossed members and a yoke means adapted to engage the shank portion of a shoe sole whereby fingers on the crossed members are drawn into gripping and operative relation with the welt of a shoe.

Another feature of the invention resides in providing an antislipping device which is maintained in operative relation with a shoe by a resilient connection with a novel expansible yoke member adapted to engage the shank of the shoe sole.

A further feature of the invention resides in providing an antislipping device having a pair of crossed members, pivotally connected at a point spaced forwardly of the place of crossing, and formed with fingers for overlying and gripping the shoe welt.

Other objects and features will hereinafter appear.

55 In the drawings:

Figure 1 is a bottom view of the device showing the same applied to a shoe sole.

Fig. 2 is a side view of the device shown in Fig. 1.

Fig. 3 is an exploded perspective view of the 5 expansible yoke member.

Fig. 4 is a bottom view similar to Fig. 1, but showing a modified form of the invention.

Fig. 5 is a side view of the form of the invention shown in Fig. 4. 10

Fig. 6 is a detail view showing a modified connection between the crossed members.

Before describing the present improvements and mode of operation thereof in detail it should be understood that the invention is not limited 15 to the details of construction and arrangement of parts shown in the accompanying drawings, which are merely illustrative of the present preferred embodiments, since the invention is capable of other embodiments, and the phraseology 20 employed is for the purpose of description and not of limitation.

Referring more particularly to the drawings for the present preferred embodiments of the invention and first to Figs. 1 through 3, there is disclosed for the purpose of illustration an antislipping device 10 applied to the sole 11 of a shoe 12.

As there shown, the device 10 includes a pair of pivotally associated and crossed members 13 and 14, formed by metal strips, which are adapted to be positioned beneath the shoe sole to respectively extend diagonally from one side thereof to the other. Provided at the forward ends 15 and 16 of the crossed members 13 and 14 are 30 inturned fingers 17 and 18 respectively adapted to overlie the welt portion 19 of the shoe sole, while at the rear ends 20 and 21 of the crossed members 13 and 14 there are preferably provided like inturned fingers 22 and 23 respectively, 35 adapted to overlie the welt of the shoe sole at points spaced rearwardly from the fingers 17 and 18.

Of importance it is to be noted that the crossed members are provided with inwardly extending 45 sections 24 and 25 respectively, located forwardly of the place of crossing 26 and connected by a pivot pin 27 having portions 28 and 29 respectively overlying and underlying the sections 24 and 25 to thus pivotally associate the members 50 13 and 14.

Likewise, it is to be noted that the cross member 14 at the place of crossing is formed with a channel shaped section 30 adapted to receive the other cross member 13. The provision of this 55

channel shaped section is advantageous in that it enables a close positioning of both the upper member 13 and the lower member 14 flat against the underside of the shoe sole and serves also as 5 a means to guide and maintain the members 13 and 14 in proper association.

Supplementing the channel section 30 in thus 10 properly maintaining the crossed members 13 and 14 in association there are preferably formed 15 in the respective members at the place of crossing 26 slots 31 and 32 adapted to slidably receive a pin 33 having a portion 34 overlying the upper member 13 and a portion 35 underlying the lower member 14.

15 Of importance, because of the connection between the crossed members at the pivot pin 27 and also at the place of crossing 26 the strength 20 of the device 10 is materially increased, and this without appreciably increasing the weight of the device.

With this construction when the crossed members 13 and 14 are pivoted relative to each other to move the gripping fingers 17, 18, 22 and 23 toward the shoe weld 19 the pin 33 slides in the 25 slots 31 and 32 and serves to strengthen the device and to maintain the members 13 and 14 in close relation.

Spikes 36 suitably secured to the crossed members and projecting downwardly therefrom provide efficient means for engaging in antislipping 30 relation with the walking surface. Preferably, and as shown, the pins 27 and 33 by which the crossed members 13 and 14 are maintained in proper association, are formed with downwardly 35 projecting portions providing spikes 37 and 38 similar to the spikes 36.

For maintaining the fingers 17, 18, 22 and 23 in firm gripping engagement with the shoe welt to 40 thus hold the antislipping device 10 in proper relation with the shoe there is preferably provided a novel yoke member 39 adapted to be located under the shank or instep portion 58 of the shoe sole and to grip the shoe welt 19 at opposite sides thereof. The yoke member may be an integral or non-expansible element.

45 Preferably, however, and as shown, this yoke member 39 is expansible so as to be readily adjustable to be efficiently cooperable with shoes having shank portions of divers widths. It includes a pair of slidably and pivotally associated bars 40 and 41 having respectively at the outer ends 42 and 43 thereof, upstanding flanges 44 and 45 with hooked portions 46 and 47 providing fingers 48 and 49 adapted to extend over the welt 19 at opposite sides of the shoe.

50 For thus pivotally and slidably associating the bars 40 and 41 of the expansible yoke member there is formed in one of the bars 40 a longitudinally extending slot 50 adapted to receive a pin or stud 51, having an enlarged head 52, on the other bar 41. An enlarged head receiving opening 53 at one end of the slot 50 permits the ready insertion of the stud 51 in the slot. When the stud 51 is subsequently slid in the slot 50 the head 52 overlies the bar 40 and serves to maintain it in pivotal and slidable relation with the other bar.

55 In order that the pivotal movement between the bars 40 and 41 may be limited to one direction, 70 toward the rear or heel portion (not shown) of the shoe, there is formed at the forward edge 54 of the bar 41 at a point on the opposite side of the stud 51 from the finger 49, an upstanding flange or ear 55 adapted to engage with the forward edge 56 of the other bar. Preferably and

as shown, the forward edge 56 is formed with a plurality of notches 57 therein adapted to receive the stop flange 55 and thus lock the bars from relative longitudinal sliding movement.

In applying the expansible yoke member to a shoe, the bars 40 and 41 are first pivoted rearwardly about the stud so as to free the stop 55 from the notched edge 56 and then slid relative to each other until the width of the member is slightly in excess of that of the narrowest part 10 of the shank portion 58. The yoke member is then inserted under the shank 58 of the sole 11 and the bars 40 and 41 pivoted forwardly until the stop 55 engages the notched edge 56. When thus adjusted the yoke member is of a width less than that of the forward ball portion 59 of the sole and of the forward portion of the shank 58 so that when pulled forwardly it will wedge against the sides of the latter portion.

To thus pull the yoke member 39 forwardly 20 to wedge the overlying fingers 48 and 49 against opposite sides of the shoe sole and to maintain the stop 55 firmly in the selected one of the notches 57 there is provided a pair of spring connectors 60. Each of these connectors comprises a coil spring 61 having a link 62 secured to the forward end and fixed as by a rivet 63 to one of the upstanding portions 64 and 65 of the fingers 13 and 14, and having a second link 66 secured to the rear end and fixed, as by a rivet, to one of the upstanding flanges 44 and 45 of the yoke member 39.

Concurrently with the pulling of the yoke member 39 into wedging engagement with the sole, the spring connectors 60 draw the pivotally associated crossed members 13 and 14 together to cause the fingers 17, 18, 22 and 23 to grip and overlie the shoe welt and thus securely maintain the antislipping device 10 in association with the shoe sole.

With this construction it will be readily appreciated that the device 10 is adapted to be applied to shoes of divers sizes and that when so applied the spring connectors 60 will automatically move the gripping fingers 17, 18, 22 and 23 in operative relation with the welt 19. Also, it will be readily appreciated that because of the manner in which the yoke member 39 is associated with the shoe that the danger of the same being knocked or jarred from operative engagement with the shoe sole is minimized.

55 Instead of the construction disclosed in Figs. 1 and 2, the modified antislipping device 70 shown in Figs. 4 and 5 may be utilized.

There it is seen that the modified device 70 like the form first described, includes a pair of pivotally associated and crossed members 71 and 72 having forward ends 73 and 74, and rear ends 75 and 76, adapted to be located beneath the sole 11 of a shoe 12 to extend diagonally from one side thereof to the other. Also as in the form first described, inturned fingers 77 and 78 are formed on the forward ends of the members 71 and 72 respectively, adapted to grip and overlie a shoe welt, and similar inturned fingers 79 and 80 are formed on the rear ends of the members 71 and 72 adapted to grip and overlie the welt 19 at points spaced rearwardly of the fingers 77 and 78.

60 It is to be noted, however, that in the modified device 70 the pivotal association of the members 70 71 and 72 is not achieved by a pin connection located forwardly of the place of crossing 81. Instead, the pivotal association of the members 71 and 72 is achieved solely by a pivot pin 82 having portions 83 and 84 overlying and underlying the 75

members 71 and 72 respectively, and connecting the same at the place of crossing.

Preferably and as shown, this pin 82 passes through longitudinally extending slots 85 and 86 in the members 71 and 72, similar to the slots 31 and 32 in the form first described. As in the form shown in Figs. 1 and 2, one of the crossed members 72 is formed with a channel shaped section 87 adapted to locate and receive the other member 71.

A projecting portion 88 on the pivot pin 82 forms a spike which cooperates with a plurality of other downwardly extending spikes 89 on the crossed members in providing an antislippling means for engaging the walking surface.

A spring plate 90 extending between the forward gripping fingers 77 and 78, and connected to the upstanding portions 91 and 92 thereof serves to hold the crossed members 71 and 72 in proper relation and to prevent adverse shifting of the pivot pin 82 in the slots 85 and 86 after the device 70 has been adjusted to fit a shoe of a given size. In addition, the spring plate 90 serves to equalize transverse forces to which one of the cross members might be subjected by distributing the same partially to the other member.

For drawing and maintaining the fingers 77, 78, 79 and 80 in gripping engagement with the welt of the shoe the same advantageous yoke member 39 and resilient connectors 60 disclosed in Figs. 1 through 3 are preferably utilized, the connection between the links 62 at the forward end of the springs 61 and the upstanding portions 93 and 94 of the fingers 78 and 80 being suitably achieved by rivets 63.

If desired there may be provided, as shown in Fig. 6, a spring plate 95 suitably secured to the member 72 to overlie the channel shaped section 87 and thus positively confine the other member 71 therein. When such a construction is utilized it is possible to dispense with the pin 82 and slots 85 and 86 connection disclosed in Figs. 4 and 5, the overlying spring plate 95, channel section 87 and connecting spring plate 90 alone serving to effectively maintain the crossed members in pivotal relation.

Also, if desired the overlying spring plate 95 may be utilized in the form shown in Figs. 1 and 2, in which event the pin 33 and slots 31 and 32 connection may be dispensed with without adversely affecting the firm and secure relationship between the crossed members.

In all of the forms, therefore, it is seen that the antislippling device provided by the present invention is simple in construction, efficient and readily adaptable for use with shoes of diverse sizes and shapes.

Variations and modifications may be made within the scope of this invention and portions of the improvements may be used without others.

Having thus described the invention, what is claimed as new is:

1. An antislippling device to be applied to the sole of a shoe or the like, including a pair of pivotally associated members adapted to be positioned beneath the sole and to respectively extend diagonally from one side thereof to the other; means on each of said members for gripping the welt of a shoe at opposite sides of the shoe sole; downwardly projecting means on at least one of said members; a substantially rigid yoke member insertable under the shank portion of a shoe sole having inturned fingers for overlying the welt of a shoe at opposite sides thereof; and resilient means connecting each of said pair

of crossed members to said yoke member for drawing said gripping means and said yoke member into operative relation with the shoe sole.

2. An antislippling device to be applied to the sole of a shoe or the like, including a pair of pivotally connected and crossed members adapted to be positioned beneath the sole of a shoe and to respectively extend diagonally from one side thereof to the other; projecting means on at least one of said crossed members for engaging a walking surface; inwardly extending fingers on each of said crossed members for gripping and overlying the welt of a shoe at opposite sides of the sole; a pair of slidably and pivotally associated bars having a pin and slot connection, one of said bars having a notched edge and the other of said members having a stop means engageable with said notched edge to prevent sliding movement between said bars and to prevent pivotal movement thereof in one direction; means on said bars for engaging opposite sides of the shank portion of the shoe sole; and resilient means connecting each of said members to said bars for drawing said gripping means into operative relation with the shoe sole and for maintaining the stop means in engagement with the notched edge.

3. An antislippling device to be applied to the sole of a shoe or the like, including a pair of crossed members adapted to be positioned beneath the sole of a shoe; sections on each of said crossed members, located forwardly of the place of crossing and respectively extending inwardly toward each other; a pivotal connection between said inwardly extending sections; projecting means on at least one of said members for engaging a walking surface; inturned fingers on said members for gripping and overlying the welt of a shoe; and means for moving said crossed members to draw said inturned fingers into operative relation with the welt of a shoe.

4. An antislippling device to be applied to the sole of a shoe or the like, including a pair of crossed members adapted to be positioned beneath the sole of a shoe; sections on each of said crossed members, located forwardly of the place of crossing and respectively extending inwardly toward each other; a pivotal connection between said inwardly extending sections; a channel shaped section in one of said members at the place of crossing for receiving the other crossed member; projecting means on at least one of said members for engaging a walking surface; inturned fingers on said members for gripping and overlying the welt of a shoe; and means for moving said crossed members to draw said inturned fingers into operative relation with the welt of a shoe.

5. An antislippling device to be applied to the sole of a shoe or the like, including a pair of crossed members adapted to be positioned beneath the sole of a shoe to respectively extend diagonally from one side thereof to the other; forward and rear ends on said crossed members; a spring plate connecting said forward ends; means on said forward and rear ends for gripping the welt of a shoe; projecting means on at least one of said members for engaging a walking surface; and means for drawing said gripping means into operative relation with the welt of a shoe.

6. An antislippling device to be applied to the sole of a shoe or the like, including a pair of crossed members respectively having longitudinally extending slots angularly disposed relative to and overlapping each other at the place of

crossing and adapted to be positioned beneath the sole of a shoe to respectively extend diagonally from one side thereof to the other; a pin in said slots and slidably therein for pivotally associating said members; forward and rear ends on said crossed members; inturned fingers on said forward and rear ends for gripping and overlying the welt of a shoe; downwardly projecting means on at least one of said crossed members; a yoke member insertable under the shank portion of a shoe sole, having hooked portions adapted to overlie the welt of a shoe; and resilient means connecting the rear end of said crossed members and said yoke member for drawing the inturned fingers into operative relation with the welt of a shoe.

7. An antislipping device to be applied to the sole of a shoe or the like, including a pair of pivotally associated and crossed members adapted to be positioned beneath the sole of a shoe and to respectively extend diagonally from one side thereof to the other; a spring plate secured to one of said members and overlying the other of said members at the place of crossing for maintaining the same in pivotal association; forward and rear ends on said crossed members; fingers on said forward and rear ends for gripping the shoe sole at opposite sides thereof; downwardly projecting means on at least one of said crossed members; and means for drawing said fingers into operative relation with the shoe sole, said means including a resilient connection to the rear end of each of said crossed members and extending rearwardly therefrom.

8. An antislipping device to be applied to the sole of a shoe or the like, including a pair of crossed members adapted to be positioned beneath the sole of a shoe or the like and to respectively extend diagonally from one side thereof to the other; means on said members for gripping the welt of a shoe at opposite sides thereof; a channel shaped section in one of said members at the place of crossing for loosely receiving the other crossed member; a spring plate overlying said channelled section in one of said members for maintaining the other member in pivotal association therewith; projecting means on at least one of said crossed members for engaging a walking surface; means insertable under the shank portion of a shoe sole, having hooked portions adapted to engage the shank at opposite sides thereof; and resilient means connecting said shank engaging means and said crossed members for drawing said gripping means into operative relation with the sole of a shoe.

9. An antislipping device to be applied to the sole of a shoe or the like, including means adapted to be positioned beneath the sole of a shoe, having a plurality of projections thereon for engaging a walking surface; means on said first named

means for gripping the welt of a shoe; yoke means insertable under the sole of a shoe, connected to said first named means for maintaining said gripping means in operative relation with the sole of a shoe, said yoke means comprising a pair of slidably and pivotally associated bars having a pin and slot connection, one of said bars having a notched edge and the other of said members having a stop means engageable with said notched edge to prevent sliding movement between said bars and to prevent pivotal movement thereof in one direction; and means on said bars for engaging opposite sides of the shank portion of the shoe sole.

10. An antislipping device to be applied to the sole of a shoe or the like, including a pair of crossed members having respectively slots angularly disposed relative to each other at the place of crossing and adapted to be positioned beneath the sole of a shoe; pin means connecting said members and slidably in said slots; a pivotal connection between said members located forwardly of the place of crossing; means on said members for gripping and overlying the welt of a shoe at opposite sides thereof; downwardly projecting means on at least one of said members; and means for moving said crossed members to draw said gripping means into operative relation with the welt of a shoe.

11. An antislipping device to be applied to the sole of a shoe or the like, including a pair of pivotally connected and crossed members adapted to be positioned beneath the sole of a shoe to respectively extend diagonally from one side thereof to the other; forward and rear ends on said crossed members; a spring plate connecting said forward ends; means on said crossed members for gripping the welt of a shoe; projecting means on at least one of said members for engaging a walking surface; and means for drawing said gripping means into operative relation with the welt of a shoe.

12. An antislipping device to be applied to the sole of a shoe or the like, including a pair of crossed members respectively having slots angularly disposed relative to each other at the place of crossing and adapted to be positioned beneath the sole of a shoe to respectively extend diagonally from one side thereof to the other; a pin in said slots and slidably therein for pivotally associating said members; forward and rear ends on said crossed members; inturned fingers on said forward and rear ends for gripping and overlying the welt of a shoe; a spring plate connecting forward ends on said crossed members; downwardly projecting means on at least one of said crossed members; and means for drawing said gripping fingers into operative relation with the welt of a shoe.

GEORGE A. MORIARTY. 60
